UNITED STATES PATENT OFFICE.

JAMES FRANCIS HICKIE, OF SLEVOIR, ROSCREA, IRELAND.

CIGAR-CABINET.

SPECIFICATION forming part of Letters Patent No. 310,942, dated January 20, 1885.

Application filed June 16, 1884. (No model.)

To all whom it may concern:

Be it known that I, JAMES FRANCIS HICKIE, a subject of Her Majesty the Queen of Great Britain, and residing at the Junior United 5 Service Club, London, England, and Slevoir, Roscrea, Ireland, have invented a new and useful Cigar Box or Cabinet, of which the following is a specification.

My invention relates to improvements in 10 cigar boxes or cabinets constructed and arranged with a view to prevent fraudulent tampering with the contents thereof after the same has been charged with cigars of any given brand, the said improved cigar box or cabinet 15 also effecting the self-delivery of the cigars therefrom as they are required for use without affording access to the interior thereof. I attain these objects by the box and mechanism contained therein illustrated in the accompanying drawings, in which—

Figure 1 is a vertical section of my improved cigar box or cabinet complete, taken along the line 1 2 in Figs. 2 and 4. Fig. 2 is a horizontal section taken partly along the line 3 4 25 and partly along the line 5 6 in Fig. 1. Fig. 3 is a vertical section of the lower part only of the cabinet, also taken along the line 1 2 in Figs. 2 and 4, but showing the mechanism in a different position. Fig. 4 is a front elevation of the 30 cabinet, showing a portion thereof in transverse vertical section taken along the line 7 8 in Figs. 1, 2, and 3, and looking from the front of the cabinet; and Fig. 5 is a transverse vertical section of the cabinet, taken along the 35 line 9 10 in Figs. 1 and 2, and looking from the back thereof.

Similar letters refer to similar parts throughout the several views.

A is the body of the cigar box or cabinet, 40 composed of wood, metal, or other suitable material, and of any design or shape, according to taste. It may be supported on feet or legs (not shown in the drawings) of any ornamental design, and is provided with a lid or 45 cover, B, on the top, which is capable of being locked or otherwise securely closed, and when closed and filled with cigars is, for greater security against fraud, sealed or otherwise protected by a trade-mark or other label constituting a guarantee of the quality or brand 50 of the cigars which it contains. Consequently

the refilling or the replenishing of the same by the addition of other cigars of an inferior quality to the brand with which it was originally supplied cannot be effected without detection by reason of the destruction of the seal or label involved in the opening of the cabinet, while the delivery or discharging mechanism is so arranged as effectually to prevent the introduction of a cigar otherwise than 60 through the open top of the cabinet.

C is a transverse vertical partition separating the cigar-holding portion of the cabinet from the chamber containing the mechanism which effects the delivery of the cigars as required for use, and which serves to check the fraudulent introduction of a cigar into the cabinet back through the delivery-aperture, as hereinafter explained, said mechanism being inclosed in a separate compartment, D, of 65 any suitable shape, according to the general form or design of the cabinet.

In my drawings, for the sake of greater simplicity, I have merely shown a plain, rectangular box with a compartment, D, in the rear 75 portion, extending from bottom to top, for inclosing the mechanism. The main portion of the cabinet is subdivided by the partitions E E into any number of narrow vertical compartments, a, (five being shown in my drawings,) each compartment extending from top to bottom of the cigar-holding portion or magazine of the box or cabinet. These vertical compartments are each of a width sufficient only to contain a single vertical row of cigars 80 placed horizontally therein, and lying one above another, as shown by the dotted lines in Figs. 1 and 4. They are left open or fully exposed for charging or refilling when the lid or cover B is opened for that purpose, but are 85 each closed at the bottom by a hollow rotating cylinder, b. An opening, c, (shown clearly in Fig. 4,) is made longitudinally in the side of each cylinder, of a width and length sufficient to admit of the entrance sidewise of 90 a single cigar at a time into the interior of the hollow cylinder when turned with its open side upward, as shown at the middle compartment in Fig. 4. When in the reversed position—namely, with the open side downward, 95 as shown at the right-hand compartment in Fig. 4—the lowest cigar of the vertical row in the

corresponding compartment, *a*, rests upon the closed convex side or surface of the hollow cylinder *b*, which thus supports the entire vertical row of cigars in the compartment above.

5 The front ends of the several cylinders are supported by and are free to rotate in a suitable bearing formed in the lower part of the front of the cabinet, and the rear ends are supported by and are free to rotate in corresponding bearings formed in the rear transverse vertical partition, *C*. The outer or front ends of the several cylinders are flush with or may project more or less through the front of the box or cabinet, and are each provided at 10 that end with means for facilitating the turning of each cylinder as required—such, for example, as a key-hole, *d*, for the reception of a key of any suitable form, or a convenient knob, *e*, turned by the finger and thumb of the operator, or a small lever-handle, *f*, (see Fig. 6,) the position of the handle serving also to indicate the position of the opening in the side of the corresponding cylinder. The normal position of the cylinder is shown in the right-hand compartment in Fig. 4—namely, with the opening *c* downward; but on turning the cylinder half-round, or into the position shown in the second compartment from the right—namely, with the opening upward—the lowest cigar 15 of the vertical row above will drop into the hollow of the said cylinder, and on completing the revolution the said cigar will drop out of the cylinder into the receiving-chamber *g* below, from which it is delivered or discharged longitudinally through an open mouth in the front of the cabinet by the action of a spring striker or propeller working through the inner end of the chamber *g*, as hereinafter described. On the rear end of each cylinder 20 there is formed, either in one piece therewith or in a separate piece screwed or otherwise secured to a journal at the rear end of the cylinder, and in the axial line thereof, a cylindrical scroll-cam, *h*, round the surface of which 25 is formed a spiral groove, making one turn round the cam, as shown clearly in Figs. 1, 2, and 3, each end of the spiral groove opening into or communicating with a short straight groove, *i*, made parallel to the axis of the cam and cylinder, as seen in Figs. 2 and 3.

30 *h* is a propeller or striker for discharging the cigar from the receiving-chamber *g* so soon as it has been dropped therein from the corresponding cylinder above. Each striker consists of a sliding piece moving longitudinally in the direction of the center line of the corresponding receiving-chamber, and supported and guided by a pin, *l*, sliding freely inside a corresponding longitudinal bore in the center 35 of each cylindrical scroll-cam, and further guided and maintained in proper position laterally by the striker-pin *k*, (shown in dotted lines in Fig. 2 in its different positions,) which works freely through an opening in the rear 40 end of the corresponding receiving-chamber, *g*. A projection, *m*, on each striker engages with

the spiral groove of the scroll-cam, (see Figs. 1 and 3,) so that when the latter is rotated in the proper direction (shown by the arrows) the cam-groove forces back the striker against a 45 helical or other spring, *n*, into the position shown in Fig. 3—that is to say, cocked and ready for action. By the time the revolution of the cam is nearly completed the said projection *m* will be on the point of entering the straight portion *i* of the cam-groove, (see the middle compartment of Fig. 2,) and being released by entering the groove *i* on the completion of the revolution of the cam will be suddenly and forcibly propelled forward by the 50 helical spring *n* into the position shown in Fig. 1, thereby propelling the cigar through the open mouth of the receiving-chamber. The cigars, when placed in their compartments, are by preference disposed with their small or 55 twisted ends to the front, so that when they are dropped singly into the receiving-chambers from the hollow cylinders their larger ends will be presented to the action of the propellers or strikers, and their small ends to 60 the exit-mouth of the said chamber, as shown clearly in Fig. 3, thus facilitating their free discharge and avoiding all chance of injury to the cigar.

In order to prevent any possibility of fraud 65 by the introduction of a cigar back through the receiving-chamber *g* and cylinder *b*, I employ a self-acting guard-arm or check apparatus, which I shall now proceed to describe.

o is a rocking spindle turning in bearings 70 *p* and formed with a crank or arm, *q*, the whole being sunk into a groove or recess in the side *E* of each compartment, so as to lie flush therewith when not in action. The said rocking spindle is further provided or formed 75 at its rear end with a short lever-arm, *r*, acted upon so as to be raised at each revolution of the cylinder by a projection or pin, *s*, on the side of the scroll-cam *h* or on the face of a ratchet-wheel, *t*, fixed to the said cam, a detent, *u*, engaging with the teeth of the ratchet-wheel, preventing the cylinder being rotated in the reverse direction to that shown by the arrows. The projection or pin *s*, by acting 80 on the short lever-arm *r*, causes the same to 85 be raised and the rocking spindle *o* to rock in its bearings, whereby the crank or arm *q* of the check apparatus is caused to move outward from the side of the vertical compartment and to enter the hollow cylinder just as the opening *c* in the side of the said cylinder 90 is brought opposite to the end of the said arm, as shown at the second compartment from the right in Fig. 4, the arm or crank *q* returning again under the action of the spring *r'* on 95 the lever *r* to its original position flush with the side of the compartment just before the opening in the cylinder has passed it. The projection or pin *s* should be so situate in relation to the opening in the cylinder as to be 100 timed to operate in the manner above set forth, and a portion of the projection may be 105 110 115 120 125 130

made concentric in order that the cranked part *q* of the guard may, if found requisite, be caused to pause or dwell for a short time after it has entered into the interior of the cylinder 5 and before leaving it.

So long as the apparatus is used legitimately, it is obvious that the crank *q* will, when the cylinder and cam *h* are rotated in the direction of the arrow, enter the empty 10 space in the cylinder through the lateral opening *c* and recede again under the action of the spring *r* once for each revolution; but in the event of a cigar having been fraudulently inserted into the cylinder from the receiving- 15 chamber *g* its presence will obstruct the inward movement of the crank *q*, thereby preventing the lifting of the lever-arm *r* and checking the further rotation of the cylinder in the direction required, and as the cylinder 20 cannot be turned in the reverse direction, owing to the ratchet-wheel *t* and detent *u*, the fact that the apparatus has been tampered with will be at once detected by the state of the mechanism.

If desired, panels of glass, as shown at *w*, 25 Figs. 1 and 4, may be let into the front or sides and top of the box or cabinet to enable the cigars in the vertical compartments to be inspected from the outside, and any well-known 30 counter may obviously be worked from the cylinders, so as to indicate on a dial the number of cigars delivered; but this forms no part of my present invention.

x is a separate removable lid or cover, which 35 may or may not be employed for closing in the compartment *D* containing the main portion of the mechanism when the lid *B* of the cabinet is open and for affording a ready means of access to the works for inspection or repairs, 40 for which purpose also the back of the box may, if desired, be made removable, as shown by the dotted lines in Fig. 1, it being maintained in position by pins or dowels, for example, at the bottom and by a button or other 45 simple fastening, *y*, at the top. Should it be required to withdraw a cylinder, for example, first remove the back of the box, then withdraw the striker and unscrew the corresponding scroll-cam with its ratchet-wheel from the 50 end of its cylinder, when the latter will be free to be withdrawn from the front of the box. The upright partitions *E* may also, if desired, be made to slide out, as well as the upper part of the transverse partition *C*, for the facility 55 of affording free access to the rocking spindle *o* of the guard or other check apparatus.

What I claim, and desire to secure by Letters Patent of the United States, is—

1. The combination, in a detector cigar box or cabinet, for preventing the fraudulent use *cc* thereof, of the following instrumentalities: first, a box or case having one or more compartments to receive separate rows of cigars, and adapted to be locked or sealed; second, a rotatable hollow slotted cylindrical delivering 65 device located at the end of each of said compartments; third, a receptacle to receive the cigar as it escapes from said delivery device; fourth, a device, substantially as described, actuated by the delivering device to eject the 70 cigar from the said receptacle; and, fifth, a guard or detent, also operated by the delivering device, to prevent the insertion of a cigar into the cabinet or case through the said delivering device, as set forth. 75

2. The combination, in a cigar case or cabinet substantially as described, of the delivering-cylinder and the expelling or discharging device consisting of the striker adapted to be withdrawn by a scroll-cam on the delivering 80 device, and a spring to impel the striker forward when it has reached its extreme withdrawn position on the cam, as set forth.

3. The combination, in a cigar case or cabinet having the delivery-cylinder, substantially 85 as described, of the guard or check device consisting of a rocking spindle carrying a crank-arm operated by a cam projection rotating with the said delivery-cylinder, said arm being caused to enter and leave the cylinder laterally once at each revolution thereof, as and for the purpose specified. 90

4. The combination, in a cigar box or cabinet, of the narrow compartment *a*, slotted rotating delivery-cylinder *b*, and rocking guard 95 or check arm *q*, actuated from the said cylinder, as and for the purpose specified.

5. The combination, in a cigar box or cabinet, of the narrow compartment *a*, slotted rotary delivery-cylinder *b*, guard or check arm 100 *q*, receptacle *g*, and spring-actuated striker or expeller *k*, working through the inner end of said receptacle, as and for the purpose specified.

In witness whereof I have signed my name 105 in the presence of two subscribing witnesses.

JAMES FRANCIS HICKIE.
